[57] CLAIM

The ornamental design for a glass bead machine cabinet for use in the dry blast cleaning of metal parts, as shown.

DESCRIPTION

FIG. 1 is a perspective view of a glass bead machine cabinet for use in the dry blast cleaning of metal parts showing our new design.

FIG. 2 is a top plan view thereof.

FIG. 3 is a bottom plan view thereof.

FIG. 4 is a rear elevation view thereof.

FIG. 5 is a left side elevation view thereof.

FIG. 6 is a front elevation view thereof.

FIG. 7 is a right side elevation view thereof.

The characteristic feature of our design resides in the specific appearance of the recessed upper panel of the cabinet.
